(57) **CLAIM**

The ornamental design for a communication module for radio thermostat, as shown and described.

DESCRIPTION

The communication module for radio thermostat is used with and mounted to a radio thermostat to permit the radio thermostat to communicate with other devices. The thermostat may be of the type used in residential and commercial buildings.

FIG. 1 is a front, right side, top perspective view of a Front Housing for Thermostat showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a bottom plan view thereof; and,

FIG. 7 is a front elevational view of an alternative embodiment thereof.

The broken line showing of structural features is included for the purpose of illustrating non-claimed subject matter and forms no part of the claimed design.
